UNITED STATES PATENT OFFICE.

PETER J. MAYER, OF MONTROSE, MISSOURI.

METAL ARCH.

1,074,001.

Specification of Letters Patent. Patented Sept. 23, 1913.

Application filed June 5, 1911. Serial No. 631,362.

To all whom it may concern:

Be it known that I, PETER J. MAYER, a citizen of the United States, residing at Montrose, in the county of Henry and State 5 of Missouri, have invented certain new and useful Improvements in Metal Arches; and I do hereby declare the following to be a full, clear, and exact description of the invention, such as will enable others skilled in 10 the art to which it appertains to make and use the same.

My invention relates to adjustable metal arches used as voissoirs in the construction of concrete or stone culverts, bridges, cellars and the like.

An object of my invention is to improve and simplify devices of this character, rendering them comparatively simple and inexpensive to manufacture, reliable and efficient 20 in use, and readily operated.

With the above and other objects in view, this invention resides in the novel features of construction, formations, combinations and arrangements of parts to be hereinafter 25 more fully described and claimed, and illustrated in the accompanying drawings, in which—

Figure 1 is a perspective view through a culvert bridge or the like, showing my improved metal arches applied in constructing the same, and Fig. 2 is a perspective view of band connection of the same.

Referring now more particularly to the drawing, wherein like parts are indicated 35 by like characters, the arch is made of sheet metal or the like, and comprises three members, the arch member 1 and the two base or supporting members 2 and 3, which may be vertically or laterally adjusted. The arch member 1 is composed of two sections 4 and 5 hinged together, as at 6, each having depending offset portions 7 to receive the ends 40 of the base members 2 and 3.

In constructing heavy bridges and the like, 45 diagonally extending braces 8 are riveted, or otherwise secured, to the ends of each of the sections 4 and 5, whereby any pressure upon the arch will be carried through the braces to the side walls, and to also brace the 50 curved portion of the arch, auxiliary V-shaped braces are provided, which are riv-

eted, or otherwise secured, to the diagonal braces 8 and sections 4 and 5.

The base or supporting members 2 and 3, each comprise two sections 10 and 11, one 55 end of the lower section 10 being bent at right angles, and has hinged thereto, as at 12, the upper section 11. The lower section 10 of the member 3 is provided with two upwardly extending lugs 13, and the 60 lower section of the member 2 is provided with a plurality of apertures 14, in which the lugs are to be inserted, whereby the members 2 and 3 may be held the desired distance apart.

The offset portion 7 of the arch sections 4 and 5 are each provided with lugs 15, and the sections 11 of the base members 2 and 3 are provided with a plurality of apertures 16, through which extend the lugs 15, to 70 hold the arch at any desired height.

The lugs 13 and 15 are threaded to receive nuts whereby the sections may be securely held together and when the frames are adjusted to a greater height plates 17 may be 75 secured to the lugs between the ends of the sections 11 and the curved portions of the sections 4 and 5 of the arch member 1 thereby forming a smooth and straight connection between the same.

In use, my improved arches are first adjusted to the desired size and then set up, as clearly shown in Fig. 1. Boards 18 are then arranged across the same and concrete 85 19 or other suitable plastic material, is filled in against these boards. Any means desired may be employed for forming the parapet and the side walls of the structure shown. It will be understood that it is not necessary to secure the boards 18 to the arches, as the 90 weight of the plastic material will hold them in position. When the plastic material has set, the nuts 13 are removed and the arches collapsed, so that they may be easily removed from the culvert. The boards 95 which form the lining of the culvert may then be also removed.

Having described my invention, what I claim as new and desire to protect by Letters Patent is:

A structure of the class described, comprising arched members hingedly connected

to each other, the free ends of said arch members being offset, base members adjustably connected at their inner ends and having their outer ends bent at an angle to the body portions, uprights hingedly connected at their lower ends to the free ends of the base members and provided with a plurality of alined openings, threaded lugs formed upon the opposite ends of the arched mem-

bers and adapted to be received in certain of 10 said openings, and nuts threaded upon the lugs.

In testimony whereof I affix my signature in presence of two witnesses.

PETER J. MAYER.

Witnesses:

FRED C. HILL,
W. F. DUGAN.
